CLAIM

The ornamental design for a vehicle wheel rim, as shown and described.

DESCRIPTION

FIG. 1 is a front right side perspective view of a vehicle wheel rim;

FIG. 2 is a rear right side perspective view thereof;

FIG. 3 is a front view thereof;

FIG. 4 is a rear view thereof;

FIG. 5 is a right side view thereof;

FIG. 6 is a left side view thereof; and

FIG. 7 is a top view thereof.

FIG. 8 is a front right side perspective view of a second embodiment of a vehicle wheel rim;

FIG. 9 is a rear right side perspective view thereof;

FIG. 10 is a front view thereof;

FIG. 11 is a rear view thereof;

FIG. 12 is a right side view thereof;

FIG. 13 is a left side view thereof; and,

FIG. 14 is a top view thereof.

Any broken lines in the figures illustrate portions of the vehicle wheel rim that form no part of the claimed design.

1 Claim, 14 Drawing Sheets
